CLAIM

The ornamental design for a shoe, as shown and described.

DESCRIPTION

FIG. 1 is a front lateral perspective view of an embodiment of a shoe, it being understood that there is no claim being made to the bottom features, other than those visible in the views of the drawing disclosure for this embodiment, therefore the bottom view of this embodiment has been omitted. FIG. 2 is a front medial perspective view of the shoe of FIG. 1.

FIG. 3 is a lateral side view of the shoe of FIG. 1.

FIG. 4 is a medial side view of the shoe of FIG. 1.

FIG. 5 is a top view of the shoe of FIG. 1.

FIG. 6 is a front view of the shoe of FIG. 1; and,

FIG. 7 is a rear view of the shoe of FIG. 1.

The broken lines immediately adjacent to shaded areas represent unclaimed boundaries of the claimed design.

The bands on the upper of the shoe are transparent and the outer side edges and the top transparent surface of the bands are claimed. The broken line circles on the interior of the bands are unclaimed.

The remainder of the shoe shown in broken lines is for environmental purposes only and forms no part of the claimed design.
